L. E. STUMP.

SIGNAL HORN.

APPLICATION FILED AUG. 12, 1911.

1,034,531.

Patented Aug. 6, 1912.

FIG. 2

UNITED STATES PATENT OFFICE.

IRA E. STUMP, OF CLEVELAND, OHIO, ASSIGNOR TO HUGH PEASE, OF CLEVELAND, OHIO.

SIGNAL-HORN.

1,034,531.

Specification of Letters Patent.

Patented Aug. 6, 1912.

Application filed August 12, 1911. Serial No. 643,687.

To all whom it may concern.

Be it known that I, IRA E. STUMP, a citizen of the United States, residing at Cleveland, in the county of Cuyahoga and State of Ohio, have invented certain new and useful Improvements in Signal-Horns, of which the following is a specification.

My invention relates to improvements in signal horns, and is particularly designed 10 and adapted for use as an exhaust blown signal horn for use in connection with automobiles, motor trucks, motor boats, and the like. When used as an exhaust blown signal horn in connection with automobiles, the 15 same is preferably connected to the exhaust pipe between the engine and the muffler, and when so used the improved horn is adapted to provide a combined signal horn and cut-out valve, the rotary valve being adapted to 20 be moved from its normal or nondiverging position to either a fluid diverting cut-out position, or a fluid diverting horn sounding position, as desired.

The primary object of the invention is to 25 provide a generally improved combined signal horn and cut-out valve of this class of exceedingly simple, cheap, and efficient construction, adapted to be readily connected to the exhaust pipe between the engine and 30 the muffler.

A further object is to provide an exhaust blown signal horn having its parts arranged and combined whereby the same may be readily operated and reducing their tendency 35 to stick or to become clogged or covered with soot or carbon to a minimum.

With the above mentioned and other ends in view, the invention consists in the novel construction, arrangement, and combination 40 of parts, hereinafter described, illustrated in one of its embodiments in the accompanying drawings, and particularly pointed out in the appended claims.

Referring to the drawings, forming a 45 part of this specification, Figure 1, is a top plan view of the improved signal horn and valve, the parts being shown in their normal or nondiverging positions, whereby the fluid or exhaust gases are passed directly into the 50 muffler. Fig. 2, a side elevation of the same. Fig. 3, a vertical longitudinal sectional view taken on line 3—3 of Fig. 1, the parts being shown in their fluid diverting whistle or horn sounding positions. Fig. 4, a cross sectional view taken on line 4—4 of Fig. 3. Fig. 5, a perspective view of the rotary

valve detached. Fig. 6, a perspective view of the rotary hood detached.

Similar numerals of reference designate like parts throughout all the figures of the 60 drawings.

The improved signal horn and valve comprises a two-part valve and horn body 1, terminating at its opposite ends in reduced pipe inlet and outlet portions 2, and 3, respectively, adapted to be suitably connected to and to form a part of the exhaust pipe leading from the engine to the muffler, the two parts of the valve and horn body being provided with attaching flanges 1^a. The 70 valve and horn body is provided with a whistle slot 4, and a cross member or partition 5, interposed between and secured to the attaching flanges 1^a, by means of attaching bolts and nuts 6. The cross member 5, 75 is provided with a centrally located fluid discharge valve opening 7, and a fluid discharge slot 8, the latter being located at the rear of the whistle slot 4, and being adapted to discharge the operating fluid to the lip 80 4^a, thereof for sounding the horn in a well known and understood manner.

As a means for opening and closing the fluid discharge opening 7, a rotary valve 9, is provided, said valve being provided with 85 oppositely extending wings adapted to extend on opposite sides of the cross member 5, and being pivotally mounted upon a pivot bar or shaft 10, the latter being mounted in suitable bearings 11, formed between the attaching flanges 1^a, of the valve and horn body 1.

As a means for operating the rotary valve 9, whereby the same may be thrown into a fluid diverting cut-out position or fluid diverting horn sounding position, one end of the pivot pin or shaft 10, is provided with a crank arm 12, connected to a wire or cable 13, leading to suitable operating mechanism, the other end of the crank arm 12, being connected to a spring 14, whereby the rotary valve 9, will be returned to and will be normally held in its normal or nondiverging position, as illustrated in Figs. 1, and 2, of the drawings.

As a means for opening and closing the whistle slot 4, when the rotary valve 9, is moved to its closed or nondiverging position or to its open or fluid diverting positions, respectively, a rotary hood 15, is pivotally mounted upon bearing lugs 16, of the horn body, said hood being provided with seg-

mental sides 15^a, forming tone modifying elements adapted to coöperate with the whistle slot 4, in controlling the pitch and tone of the horn when the latter is being operated or sounded by the passage of the operating fluid or exhaust gases through the fluid discharge slot 8, leading to the lip 4^a, of the whistle slot, as illustrated in Figs. 3, and 4, of the drawings.

10 As a means for simultaneously actuating the hood 15, with the opening and closing movements of the rotary valve 9, the shaft 10, of the latter is provided at one end with a crank arm 17, connected to a connecting arm 18, the latter being provided at one end with a guide link 18^a, having a guide slot taking over and coöperating with a guide pin 19, carried upon one side of the hood 15, whereby the latter may be operated in an obvious manner.

From the foregoing description, taken in connection with the accompanying drawings, the operation and advantages of my invention will be readily understood.

25 Having thus described one of the embodiments of my invention, what I claim and desire to secure by Letters Patent is,—

1. In a signal horn and valve, a valve and horn body comprising two parts, one of which is provided with a whistle slot, a cross member provided with a valve opening and a fluid discharge slot leading to said whistle slot, a rotary valve adapted to open and close said valve opening, and means for moving said rotary valve to a fluid diverting whistle sounding position or a fluid diverting cut-out position.

2. A signal horn, comprising a horn body provided with a whistle slot, a cross member provided with a rotary valve and a fluid discharge slot leading to said whistle slot, a rotary hood adapted to extend above and to open and close said whistle slot, and connecting mechanism for operating said rotary hood when said rotary valve is actuated.

3. In a signal horn and valve, the combination with a horn and valve body provided with a whistle slot, a cross member having a

valve opening and a fluid discharge slot and a rotary hood adapted to extend above and to open and close said whistle slot; of a rotary valve mounted in said valve opening and horn body, and connecting mechanism adapted to open and close said whistle slot as said rotary valve is moved to its closed and open positions, respectively.

4. In a signal horn and valve, a valve and horn body provided with a whistle slot and comprising two parts each part consisting of a flanged body and a reduced pipe portion, a cross member interposed between said flanged bodies and provided with a fluid discharge slot and a valve opening, and a rotary valve adapted to open and close said fluid discharge valve opening and adapted to be moved to a fluid discharge cut-out position with respect to said whistle slot.

5. A signal horn, comprising a two-part valve and horn body provided with a whistle slot, a cross member provided with a valve opening and a fluid discharge slot leading to said whistle slot, a rotary valve adapted to open and close said valve opening, and a rotary hood connected to said valve and adapted to open and close said whistle slot when said rotary valve is moved to its closed and open positions, respectively.

6. A signal horn, comprising a valve and horn body provided with a whistle slot, a cross member provided with a fluid discharge slot leading to said whistle slot, a rotary valve adapted to be moved to a fluid diverting cut-out position with respect to said whistle slot, and a hood connected to said rotary valve and adapted to open and extend above said whistle slot when said rotary valve is moved to its fluid diverting cut-out position.

In testimony whereof I have affixed my signature in presence of two witnesses.

IRA E. STUMP.
